UNITED STATES PATENT OFFICE

2,369,964

SWITCH ACTUATING MECHANISM

Robert W. Goff, Schenectady, N. Y., assignor to
 General Electric Company, a corporation of
 New York

Application January 11, 1944, Serial No. 517,813

8 Claims. (Cl. 74—100)

My invention relates to electric switch actuating mechanisms, and especially to limit switch actuating means providing for overtravel in both directions of movement of an engageable operating lever.

The invention has particular application to and has been illustrated by way of example as applied to a double-throw limit switch of the snap-action type having a switch actuating rocker lever alternatively latched in one of two predetermined spaced circuit controlling positions and slidable overcenter spring means for disengaging the latches and moving the rocker lever.

It is a general object of my invention to provide a new and improved limit switch of the above character which shall be simple in construction, inexpensive and economical to manufacture, reliable in operation, and characterized by a greatly improved operating life.

It is a more specific object of my invention to provide a new and improved switch mechanism including means for converting rotation of an engageable operating lever about one axis to rotation of a switch actuating member about a perpendicular axis while permitting overtravel of the operating lever in both directions with respect to the actuating member.

My invention itself, together with further objects and advantages thereof, may be fully appreciated by referring now to the following detailed specification taken in conjunction with the accompanying drawings, in which Fig. 1 is a front elevational view of a limit switch embodying my invention in one form; Fig. 2 is a cross-sectional view taken along the line 2—2 of Fig. 1 looking in the direction of the arrows; Fig. 3 is a rear elevational view of the limit switch of Figs. 1 and 2; Fig. 4 is an exploded perspective view of the principal operating parts of the switch shown at Figs. 1-3; and Fig. 5 is a fragmentary exploded perspective view of a part of the mechanism illustrated at Fig. 4.

Referring now to the drawings, and particularly to Fig. 1, I have illustrated my invention by way of example as embodied in an electric limit switch of the general type disclosed and claimed in my copending application Serial No. 471,137, filed January 2, 1943 and assigned to the same assignee as the instant application. The switch is mounted within a casing 10 having an internal dividing wall 11 and provided on opposite sides thereof with covers 12 and 13 to provide separate compartments 14 and 15 for the switch contacts and operating mechanism, respectively. The switch compartment 14 is provided with a gas

outlet vent 16 and a tapped conduit connection 17 for the entrance of suitable electric conducting wires.

The double-pole double-throw limit switch illustrated in the drawings comprises two spaced pairs of stationary contacts 18 and 19 and a movable bridging contact member 20. The bridging contact 20 is slidably mounted upon a rectangular contact supporting bar 21 and is resiliently held in a central position within a slidable yoke 22 by a pair of helical compression springs 23 positioned between the contact member 20 and the parallel sides of the yoke. As clearly shown at Fig. 4, the yoke 22 is slidably mounted upon the contact supporting bar 21. For the purpose of sliding the yoke 22 longitudinally of the bar 21 to move the bridging contact 20, I have provided a pin 24 extending rearwardly from the bight of the yoke 22 into a slot 25 of a pivotally mounted switch arm 26. The arm 26 forms part of a switch member comprising a rocker shaft 27 fixedly connected at one end to the arm 26 and at the other end to the center of a rocker lever 28. The rocker shaft 27 is rotatably journaled intermediate its ends in the casing partition or dividing wall 11. The rocker lever 28 forms a part of the switch actuating mechanism and lies in the compartment 15.

The switch actuating mechanism will be best understood by referring now particularly to Figs. 3 and 4. From Fig. 3, it will be observed that a pair of latch levers 29 and 30 are pivotally mounted upon pivot pins 31 and 32, respectively, in the base 10 and are biased into engagement with opposite ends of the rocker lever 28 by means of associated helical compression springs 33 and 34, respectively. The springs 33 and 34 are seated in casing abutments 35 and 36, respectively, which serve to limit the latch disengaging movement of the associated latch members.

Each latch member 29 and 30 is provided with a latching shoulder 37 with which the opposite ends of the rocker lever 28 are alternatively engageable. Each latch lever 29 and 30 is also provided with a limit stop shoulder 38 with which the opposite ends of the rocker lever 28 are also alternatively engageable in inverse relation with respect to the latch shoulders 37. That is, when the latch shoulder 37 of the lever 30 is in engagement with one end of the rocker lever 28 as shown, the stop shoulder 38 of the other lever 29 is in engagement with the opposite end of the rocker lever 28. Conversely, the latch shoulder 37 of the lever 29 and the stop shoulder 38 of the lever 30 will be simultaneously effective when the rocker

lever 28 is in its other circuit controlling position. The operation of the rocker lever 28 and the function of the latch and stop shoulders 37 and 38 will be more clearly understood after the remainder of the operating mechanism has been more fully described.

The rocker lever 28 is actuated with a snap-action between two angularly displaced limiting circuit controlling positions by means of an over-center mechanism comprising a spring pressed ball or roller 39 mounted in the movable end of a pivoted actuating lever 40 for sliding movement longitudinally of the rocker lever 28 and overcenter with respect to the rocker shaft 27. The ball 39 is biased outwardly from the end of the lever 40 by a helical compression spring 41 positioned within a counterbore in the lever 40. The actuating lever 40 itself is shown as having a rectangular cross-section, and is pivotally mounted upon a fixed pivot pin 42 in the casing 10.

Attached to the actuating lever 40 is a clutch arm comprising an offset portion 43 extending from the pivot pin 42 substantially longitudinally of an operating shaft 47. The operating shaft 47 is disposed substantially perpendicular to the pivot pin 42 and has fixed thereto a longitudinally grooved substantially cylindrical hub 46. Releasable clutching engagement between the operating shaft 47 and the actuating lever 40 is effected by a clutch pin 44 attached to the offset portion 43 of the clutch arm and extending substantially perpendicular to the operating shaft 47 into engagement with the grooved surface of the hub 46. The clutch pin 44 is hollow, or may be counterbored at its end, to receive a spring-pressed ball 45 which, together with the grooved hub 46, constitutes a releasable overriding ball and socket clutching connection between the operating shaft 47 and the actuating lever 40.

The hub 46 is shown in greater detail at Fig. 5, and comprises a cylindrical body portion grooved longitudinally at 48 along one side and enlarged at one end to provide a pair of oppositely disposed stop shoulders 49 and 50. At a portion of reduced cross-section axially displaced from the stop shoulders 49 and 50 and the grooved cylindrical portion, the hub 46 is provided with a radially extending arm 51. A C-shaped leaf spring 52 is positioned circumferentially of the hub 46 and to grasp the arm 51 firmly between the open ends of the spring. While it is, of course, not necessary that the hub 46 be of reduced cross-section in the region of the arm 51, such reduction of cross-section is desirable so that the diametrical dimension of the C-shaped spring 52 may be approximately the same as the diameter of the grooved cylindrical portion of the hub 46.

Referring now again to Figs. 2 and 4, it will be observed that the operating shaft 47 is positioned parallel to the internal dividing wall 11 and sufficiently closely thereto that the stop shoulders 49 and 50 on the hub 46 will engage the dividing wall to limit the rotation of the operating shaft 47 in both directions. Mounted upon the dividing wall 11 I also provide a fixed stop member 53 having a pair of spaced-apart dogs 54 of substantially the same width as the radial arm 51 on the hub 46. The dogs 54 are arranged on opposite sides of the arm 51 and between the open ends of the C-shaped spring 52. Thus, when no operating torque is applied to the shaft 47, the C-shaped spring 52 tends to close upon opposite sides of the fixed dogs 54 and to hold the radial arm 51 of the hub in a normal position between the dogs 54. The fixed stop member 53 carrying

the dogs 54 is slotted at 55 to provide for adjustable mounting upon the casing 10 by means of a bolt 55'. It will therefore be evident that the normal position of the operating shaft 47 may be changed within limits by adjusting the position of the fixed stop 53 upon the casing 10.

It may now be observed from Figs. 1 and 3, that the operating shaft 47 extends through a wall of the casing 10 to the outside thereof and carries at its outer end an operating arm 56 upon the end of which may be mounted an engaging roller 57. As illustrated in the drawings, the operating arm or lever 56 is preferably mounted upon the operating shaft 47 by means of a pair of serrated hubs, one upon the shaft 47 and one upon the arm 56, arranged to be locked in engagement in any one of a plurality of positions by means of a bolt 59.

From the foregoing detailed description of the various parts of my switch mechanism and the manner of their organization into a unitary whole, it is believed that the operation of the device will be evident from the following brief description. Assuming that initially the mechanism is in the position shown in the drawings, and referring particularly to Figs. 2, 3 and 4, movement of the bridging contact 20 from the position shown and into engagement with the contacts 19 is effected by movement of the operating arm 56 and shaft 47 in a counterclockwise direction, as viewed at Fig. 4. Counterclockwise rotation of the shaft 47 and the attached hub 46 moves the pin 44 on the lever 43 downwardly, as viewed at Fig. 4, by reason of the engagement of the ball 45 with the socket or groove 48. Downward movement of the pin 44 effects counterclockwise rotation of the actuating lever 40 about its pivot pin 42. Such counterclockwise rotation of the shaft 47 and attached hub 46 also causes the radial arm 51 on the hub to spread the C-shaped spring 52 by moving the lower end of the spring, as viewed at Fig. 4, away from the fixed dogs 54, while leaving the upper end of the spring in engagement with the upper sides of the dogs. The counterclockwise rotation of the actuating lever 40 thus effected continues until the free end of the lever 40 strikes the latch lever 30. During this movement, the ball 39 is moved inwardly with respect to the rocker shaft 27. However, the rocker lever 28 is not moved immediately because of its latching engagement with the shoulder 37 of the latch lever 30. As soon as the actuating lever 40 strikes the lever 30 and moves it to its latch disengaging position against the abutment 36 the rocker lever 28 is unlatched and the spring 41 becomes effective to rotate the rocker shaft 27 in a clockwise direction, as viewed at Fig. 4, until the right side of the rocker lever 28 engages the limit stop shoulder 38 of the lever 30. In this position it will be clear, by analogy with Fig. 3, that the latch shoulder 37 of the latch lever 29 has moved under the left-hand end of the rocker lever 28 to lock the rocker lever in the new position. It will be understood that rotation of the rocker shaft 27 and the attached switch arm 26 produces a sliding movement of the yoke 22 and bridging contact 20 along the contact supporting bar 21.

As mentioned hereinbefore, rotation of the operating shaft 47 in both directions from its normal position is limited by engagement of the stop shoulders 49 and 50 with the dividing wall 11 of the casing 10. However, the stop shoulders 49 and 50 are so positioned upon the hub 46 that

switch actuating movement of the rocker shaft 28 in both directions may be effected before the stop shoulders 49 and 50 engage the casing. These shoulders serve, however, to limit overtravel of the operating lever 56 with respect to the actuating lever 40. For example, in the event that, after the contact actuating movement described, a further counterclockwise rotation of the operating arm 56 is effected, the spring pressed ball 45 will be forced out of the groove or socket 48 by reason of the fact that the actuating lever 40 is now in engagement with the latch lever 30 and the latch lever 30 is in engagement with the fixed abutment 36. Thus, while no further counterclockwise rotation of the actuating lever 40 is possible, a certain degree of overtravel of the operating shaft 47 is permitted by forcing the ball 45 out of the groove 48. This overtravel is limited only by engagement of the stop shoulder 49 with the casing 10.

If now the operating arm 56 is released, the C-shaped spring 52 will assume its normal shape and bring the radial arm 51 on the hub 46 back into alignment with the protruding dogs 54 on the fixed stop 53. The operating shaft 47 and hub 46 will thus be moved in a clockwise direction, as viewed at Fig. 4, and the actuating lever 40 rotated in a clockwise direction about its pivot pin 42. Upon such clockwise rotation of the actuating lever 40, it strikes the latch lever 29 and effects snap-action of the rocker lever 28 in a manner entirely analogous to that described heretofore in connection with the latch lever 30. Such snap action of the rocker lever 28 takes place before the stop shoulder 50 on the hub 46 engages the casing 10. If, now, the operating lever 56 is forced further in a clockwise direction, the ball 45 will again be forced out of the groove 48 and overtravel of the shaft 47 permitted until the stop shoulder 50 engages the casing 10.

As noted hereinbefore, the normal positions of the operating shaft 47 and actuating lever 40 may be changed by adjustment of the fixed stop member 53. This adjustment will be more fully understood by referring again to Fig. 4. As shown at this figure, the bridging contact 20 is in engagement with the fixed contacts 18 when the switch mechanism is in its normal position. If now it is desired to maintain the contacts 18 normally open and the contacts 19 normally closed, it is only necessary to loosen the bolt 56 of Fig. 2 and slide the fixed stop member 53 downwardly, as viewed at Figs. 2 and 4. In this manner the normal position of the operating shaft 47 and hub 46 may be displaced in a counterclockwise direction from the positions shown, so that the actuating lever 40 is normally on the opposite side of the rocker lever 28 and in engagement with the latch lever 30.

From the foregoing detailed description of the structure and operation of my electric switch, the purpose and advantages of the limiting stop 38 on the latch levers 29 and 30 will become evident. Briefly, these shoulders definitely determine the circuit controlling positions of the rocker arm 28 without reliance upon the switch contacts themselves as limiting stops. By this arrangement, "backlash" in the mechanism is prevented and its operating life is considerably extended. This feature of the limit switch disclosed herein by way of illustration of a preferred embodiment of my present invention is fully described and claimed in my copending application Serial No. 471,137, referred to hereinbefore.

While I have described only a preferred embodiment of my invention by way of illustration,

many modifications will occur to those skilled in the art, and I therefore wish to have it understood that I intend in the appended claims to cover all such modifications as fall within the true spirit and scope of my invention.

What I claim as new and desire to secure by Letters Patent of the United States is:

1. A motion transmitting overtravel mechanism comprising a base, a substantially cylindrical operating member mounted upon said base for rotation about a first axis, an actuating member pivotally mounted upon said base for rotation between two angularly spaced limiting positions and about a second axis perpendicular to said first axis, and an overriding clutch arm attached to said actuating member and offset from said second axis longitudinally of said first axis, said arm extending into releasable clutching engagement with said cylindrical operating member, thereby positively to connect said operating and actuating members over a predetermined limited range of rotation of said operating member.
2. A motion transmitting overtravel mechanism comprising a base, a substantially cylindrical operating member mounted upon said base for rotation about a first axis, means for biasing said operating member to a selectable normal position, an actuating member pivotally mounted upon said base for rotation between two angularly spaced limiting positions and about a second axis perpendicular to said first axis, an overriding clutch arm attached to said actuating member at a point displaced from said second axis longitudinally of said first axis and extending into releasable clutching engagement with said cylindrical operating member, and means including said biasing means for selecting said normal position normally to dispose said actuating member in either of said limiting positions.
3. A motion transmitting overtravel mechanism comprising a base, a substantially cylindrical operating member mounted upon said base for rotation about a first axis, an actuating member pivotally mounted upon said base for rotation between two angularly spaced limiting positions and about a second axis perpendicular to said first axis, said actuating member including an overriding clutch arm offset from said second axis substantially longitudinally of said first axis and extending substantially perpendicular to said first axis into releasable clutching engagement with said operating member, and a pair of stop members carried by said operating member and disposed to engage said base to limit overtravel of said operating member in both directions and with respect to said actuating member.
4. A motion transmitting overtravel mechanism comprising a base, a substantially cylindrical operating member mounted upon said base for rotation about a first axis, means for biasing said operating member to a selectable normal position, an actuating member pivotally mounted upon said base for rotation between two angularly spaced limiting positions and about a second axis substantially perpendicular to said first axis, said actuating member including a clutch arm radially displaced from said second axis and extending substantially parallel thereto into releasable overriding clutching engagement with the cylindrical surface of said operating member, a pair of stop members carried by said operating member and arranged to engage said casing to limit the rotation of said operating member while permitting limited overtravel thereof in both directions with respect to said actuating member, and means in-

cluding said biasing means for selecting said normal position normally to dispose said actuating member in either one of said limiting positions.

5. A motion transmitting overtravel mechanism comprising a base, a substantially cylindrical operating member rotatably mounted upon said base, a pair of stop members carried by said operating member and arranged to engage said base to limit rotation of said operating member between two predetermined angularly displaced positions, an actuating member pivotally mounted upon said base for movement between two angularly spaced limiting positions and about an axis substantially perpendicular to the axis of rotation of said operating member, and a releasable overriding clutch connection between the surface of said cylindrical operating member and a portion of said actuating member offset from said pivotal axis longitudinally of said cylindrical operating member, said clutch connection effecting movement of said actuating member between said limiting positions within the limits of rotation of said operating member and permitting overtravel of said operating member in both directions.

6. A motion transmitting overtravel mechanism comprising a base, a substantially cylindrical operating member rotatably mounted upon said base, a pair of stop members carried by said operating member and arranged to engage said base to limit rotation of said operating member between two predetermined angularly displaced positions, an actuating member pivotally mounted upon said base for movement between two angularly spaced limiting positions and about an axis substantially perpendicular to the axis of rotation of said operating member, a releasable overriding clutch connection between the surface of said cylindrical operating member and a portion of said actuating lever offset from said pivotal axis longitudinally of said cylindrical operating member, said clutch connection effecting movement of said actuating member between said limiting positions within the limits of rotation of said operating member and permitting overtravel of said operating member in both directions, and adjustable means for biasing said operating member to a selectable normal position within said limits of rotation, thereby normally to dispose said actuating member in either of said limiting positions.

7. A motion transmitting overtravel mechanism comprising a base, a substantially cylindrical operating member rotatably mounted upon said

base, a pair of stop members carried by said operating member and arranged to engage said base to limit rotation of said operating member between two predetermined angularly displaced positions, an actuating lever pivotally mounted upon said base for rotation between two angularly spaced limiting positions and about an axis substantially perpendicular to the axis of rotation of said operating member, a clutch arm attached to said actuating lever and extending from said pivotal axis in a direction substantially longitudinal of said cylindrical operating member, and a spring-pressed ball and socket connection between said clutch arm and the cylindrical surface of said operating member, said operating member effecting movement of said actuating lever between said limiting positions within the limits of rotation of said operating member and said ball and socket connection permitting overtravel of said operating member with respect to said actuating lever in both directions.

8. A motion transmitting overtravel mechanism comprising a base, a substantially cylindrical operating member rotatably mounted upon said base and having a radially extending arm, a pair of stop members carried by said operating member and arranged to engage said base to limit rotation of said operating member between two predetermined angularly displaced positions, an actuating lever pivotally mounted upon said base for rotation between two angularly spaced limiting positions and about an axis substantially perpendicular to the axis of rotation of said operating member, a clutch arm attached to said actuating lever and extending from said pivotal axis in a direction substantially longitudinal of said cylindrical operating member, a spring-pressed ball and socket connection between said clutch arm and the cylindrical surface of said operating member, said operating member effecting movement of said actuating lever between said limiting positions within the limits of rotation of said operating member and said ball and socket connection permitting overtravel of said operating member with respect to said actuating lever in both directions, adjustable stop means for selectively determining the normal position of said operating member, and a C-shaped spring encircling said operating member and having its ends positioned normally to align said radially extending arm and said adjustable stop.

ROBERT W. GOFF
